(57) **CLAIM**

The ornamental design for an infrared temperature measurement device, as shown and described.

DESCRIPTION

FIG. 1 is a front view of an infrared temperature measurement device in accordance with the present invention; FIG. 2 is rear view of the infrared temperature measurement device of FIG. 1;

FIG. 3 is a left view of the infrared temperature measurement device of FIG. 1;

FIG. 4 is a right view of the infrared temperature measurement device of FIG. 1;

FIG. 5 is a top view of the infrared temperature measurement device of FIG. 1;

FIG. 6 is a bottom view of the infrared temperature measurement device of FIG. 1;

FIG. 7 is a first stereoscopic view of the infrared temperature measurement device of FIG. 1; and,

FIG. 8 is a second stereoscopic view of the infrared temperature measurement device of FIG. 1.
